UNITED STATES PATENT OFFICE.

HERMAN LEISER, OF HOUSTON, TEXAS.

DESIGN FOR A RING.

No. 39,444.

Specification for Design.

Patented Aug. 18, 1908.

Application filed May 7, 1908. Serial No. 431,544. Term of patent 14 years.

To all whom it may concern:

Be it known that I, HERMAN LEISER, a citizen of the United States, residing at Houston, in the county of Harris and State of Texas, have invented a new, original, and ornamental Design for a Ring, of which the following is a specification, reference being had to the accompanying drawing, forming part thereof.

Figure 1 is a top plan view of a ring showing my design. Fig. 2 is a perspective view of the same.

I claim:

The ornamental design for a ring, as shown.
HERMAN LEISER.
